Attn: S

UNITED STATES PATENT OFFICE.

FRED MATHEWS, OF CHICAGO, ILLINOIS.

SHOE RACK.

1,419,163.

Specification of Letters Patent. Patented June 13, 1922.

Application filed April 7, 1921. Serial No. 459,504.

To all whom it may concern:

Be it known that I, FRED MATHEWS, a citizen of the United States, residing at Chicago, in the county of Cook and State of Illinois, 5 have invented certain new and useful Improvements in Shoe Racks, of which the following is a specification.

This invention relates to door or wall racks for supporting shoes or slippers, and 10 has for its primary object to provide a rack for this purpose which is simple and economical in construction, light in weight, attractive in appearance, and convenient in use.

15 A further object is to provide a rack which will securely hold all sizes and types of shoes.

The many other objects and advantages of 20 the invention will be better understood by reference to the following specification when considered in connection with the accompanying drawings illustrating a selected embodiment thereof, in which:

Fig. 1 is a perspective view of the shoe 25 rack complete.

Fig. 2 is a plan view, and

Fig. 3 is an end elevation.

Referring to the drawings, the shoe rack is secured upon a wall or door 5 by screws 30 or other suitable means. This rack is formed of wire preferably of the resilient type. A wire 6 is provided with eyelets 7 at its ends to receive screws 8. This wire projects forwardly and downwardly and has 35 a horizontal portion 9. A wire brace 10 has its ends soldered or otherwise secured to the portion 9 of the wire 6 and an eye 11 is formed in the central portion thereof to receive a fastening screw 12. A wire 13 extends 40 between the outwardly projecting end portions of the wire 6 and is bent back and forth upon itself to form a series of substantially V-shaped shoe engaging seats 14, the various sections of the wire being preferably coiled at their junctions 15. The 45 brace 10 preferably passes through certain of these coils to support the wire 13 intermediate its ends.

The shoes are supported in the V-shaped 50 seats 14 with the sole of the shoe resting on the horizontal portion 9 of the wire 6. The shoe is inserted in the seat from above and the shank portion of the shoe moves downwardly between the wires forming the seat 55 until this portion is firmly gripped by these wires immediately in front of the heel. The

wires forming the sides of the seat pass diagonally across the front corners of the heel and thus absolutely prevent the shoe from becoming released from the rack until 60 actually lifted therefrom.

The V-shape of the seats enables any size or style of shoe to be placed in the rack.

While these seats may be formed of any suitable material, I have found it advantageous to use spring wire and to provide the coils at the junction of the various sections to facilitate the insertion of the shoe and to more securely hold the shoes in position.

The rack is easily installed and presents 70 an attractive appearance. Any number of seats may be provided.

I am aware that changes may be made in the form and arrangement of the parts without departing from the spirit of my invention, and I reserve the right to make all such as fairly fall within the scope of the following claims.

I claim:

1. A shoe rack comprising a supporting 80 frame, a plurality of substantially V-shaped shoe seats formed on said frame each adapted to grip the shank of a shoe, and a shoe rest disposed in front of said seats and below the point of gripping thereof. 85

2. A shoe rack comprising a supporting frame, a plurality of vertically disposed V-shaped shoe seats on said frame each adapted to grip the shank of a shoe, and a horizontal shoe rest in front of each of said seats 90 and below the point of gripping thereof.

3. A shoe rack comprising a wire supporting frame, a shoe holder mounted on said frame consisting of a wire bent back and forth upon itself to form a series of vertically disposed V-shaped seats lying substantially in the same plane and each adapted to engage the shank of a shoe, and a horizontal shoe rest disposed below the level of the points of engagement of said seats with 100 the shoes therein. 95

4. A shoe rack comprising a wire supporting frame, a vertically disposed shoe holder on said frame consisting of a single spring wire bent back and forth upon itself 105 to form a series of V-shaped seats each adapted to engage the shank of a shoe, and a shoe rest of wire extending longitudinally of said holder and spaced therefrom.

5. A shoe rack comprising a supporting 110 frame, a vertically disposed shoe holder on said frame consisting of a wire bent back

and forth upon itself to form a series of connected V-shaped seats, said wire being coiled at each change of direction, and a shoe rest formed on said frame in front of said holder.

6. A shoe rack comprising a wire having eyelets at its opposite extremities and the end portions of said wire projecting forwardly therefrom and then downwardly to a horizontal connecting portion, and a second wire connecting the forwardly projecting portions of the first wire and being bent back and forth on itself to form a series of vertically disposed V-shaped shoe holders, the horizontal portion of the first wire forming a shoe rest in front of said shoe holders.

7. A shoe rack comprising a wire having eyelets at its opposite extremities and the

end portions of the wire projecting forwardly and then downwardly therefrom to a horizontal connecting portion, a second wire connecting the forwardly projecting portions of the first wire and being bent back and forth on itself to form a series of vertically disposed V-shaped shoe holders, the horizontal portion of the first wire forming a shoe rest in front of said shoe holders, and a brace wire for supporting said holder and said rest intermediate their ends.

8. A shoe rack comprising a series of substantially V-shaped shoe seats each formed of resilient members adapted to grip the shank of a shoe, and a horizontal shoe rest in front of and below the shoe engaging portion of said members.

FRED MATHEWS.
